H. H. LAMPERT.
BAR SUPPORT AND CLAMPING DEVICE.
FILED OCT. 6, 1919.

FIG.1

FIG. 2

FIG. 3

Inventor
Henry H. Lampert,
By *James W. Lampert*

UNITED STATES PATENT OFFICE.

HENRY H. LAMPERT, OF CHICAGO, ILLINOIS.

BAR SUPPORT AND CLAMPING DEVICE.

Application filed October 6, 1919. Serial No. 328,737.

To all whom it may concern:

Be it known that I, HENRY H. LAMPERT, a citizen of the United States of America, and a resident of Chicago, county of Cook, 5 and State of Illinois, have invented certain new and useful Improvements in Bar Supports and Clamping Devices, of which the following is a specification.

The main objects of this invention are to 10 provide an improved bar support and spacing device for use in supporting and clamping in place the reinforcing bars used in concrete construction; to provide an improved formation of the supporting means 15 by means of which the reinforcing bars are supported above the falsework upon which the concrete is poured; to provide an improved construction and arrangement of the clamping means by which the reinforcing 20 bars are held in place on the spacing member; and to provide an improved device of this kind which is exceedingly simple and inexpensive to manufacture.

An illustrative embodiment of this invention 25 is shown in the accompanying drawings, in which—

Fig. 1 is a perspective view of one form 30 of a device constructed in accordance with this invention, a reinforcing bar being shown secured in position above one of the supporting legs.

Fig. 2 is a similar view showing a modified form of device embodying this invention.

Fig. 3 is a similar view showing still another modified form of device embodying this invention.

In the specific embodiments of the invention shown in the accompanying drawings, a 40 strip of metal 1 is doubled upon itself at predetermined intervals along its length so as to provide depending legs 2, with each of which is combined a piece of wire 3 so arranged that it may be wrapped around the 45 reinforcing bar 4 for the purpose of securing it in place.

The strip 1 is of comparatively thin, narrow sheet-metal and is preferably of uniform cross section. This strip is run 50 through a suitable machine and the bends or doubled-over portions are formed in the desired manner with the wires 3 secured in place.

In the form shown in Fig. 1, the bends 55 form a substantially W-shaped supporting leg with the doubled-over end 5 of the mid-

dle part located adjacent to the plane of the strip 1 and with the lower ends of the outside parts of said legs disposed in substantially the same plane and a predetermined 60 distance from the plane of the strip. In this modification, the wire 3 is gripped in the upper or doubled-over end 5 of the middle part of the leg and provides arms 6 which are adapted to be wrapped around the reinforcing bar 4 and have their ends twisted together so as to firmly secure said bar in place.

In the modification shown in Fig. 2, the bends are substantially the same as in Fig. 1, except the lower ends of the outside parts of the W-shaped legs are enlarged or bowed outwardly so as to provide substantially cylindrical-shaped feet or bearing members 7. The wires 3 are secured in the middle part 75 of the legs, the same as in Fig. 1.

In the modification shown in Fig. 3, the strip is doubled upon itself and bent around in the form of an "O" so as to bring the doubled-over end 8 up against the bottom 80 of the strip 1. In this form, the wire 3 is secured within the doubled-over end 8 and the arms 6 are located in substantially the same relative position as is the case in the other two modifications.

The use of these devices being well understood, no explanation of that matter is considered necessary.

Although several modifications have been herein shown and described, it will be understood that no attempt has been made to illustrate all possible modifications embodying the present invention, and it is also understood that the details of the modifications that are shown may be altered or omitted without departing from the spirit of the invention as defined by the following claims.

I claim:

1. As an article of manufacture, a unitary structure for use as a bar supporting device 100 for concrete reinforcements, comprising a strip of metal doubled upon itself to provide a transversely disposed supporting leg, and a separately formed wire clamping element secured to said strip by being gripped between the doubled-over parts of said leg and adapted to be wrapped around a reinforcing bar resting on said strip.

2. As an article of manufacture, a unitary structure for use as a bar supporting device 110 for concrete reinforcements, comprising a strip of metal of substantially uniform width

and cross-section throughout its length doubled upon itself at predetermined intervals along its length so as to provide a plurality of depending legs, and lengths of wire secured intermediate their ends between the doubled-over parts of the respective legs so as to provide arms adapted to be wrapped around reinforcing bars resting on said strip.

3. As an article of manufacture, a unitary 10 structure for use as a bar supporting device for concrete reinforcements, comprising a strip of metal doubled upon itself and bent back so as to provide a supporting leg with the end formed by the doubling of the strip 15 located adjacent to the plane of said strip, and a wire secured in said end so as to provide arms adapted to be wrapped around a reinforcing bar resting on said strip.
4. A device of the class described, comprising a strip of metal doubled upon itself 20 to form substantially a W-shaped leg, and

a wire secured between the doubled-over portions of the middle part of said W-shaped leg and providing arms adapted to be wrapped around a reinforcing bar resting on said strip. 25

5. A device of the class described, comprising a strip of metal doubled upon itself to form substantially a W-shaped leg having the upper end of the middle part located adjacent to the plane of said strip and having the lower ends of the outside parts enlarged to provide substantially cylindrical-shaped bearings members, and a wire secured between the doubled-over portions of the middle part of said W-shaped leg and providing arms adapted to be wrapped around a reinforcing bar resting on said strip. 30 35

Signed at Chicago, this 2nd day of October, 1919.

HENRY H. LAMPERT.
